UNITED STATES PATENT OFFICE.

FIRMIN M. LE COMTE, OF OCONTO, WISCONSIN.

BRAKE-BEAM SAFETY GUIDE FOR RAILWAY CARS OR COACHES.

Application filed March 12, 1926. Serial No. 94,237.

This invention relates to a brake beam safety guide for railway cars or coaches.

One object of my invention is to provide a simple, practical and economical device of this character which may be easily and readily applied and removed without first removing or interfering in any way with the brake beams.

A further object of my invention is to provide a safety guide of the character specified which may be easily and quickly removed for repairs or replacement in the event of an accident or other emergency, without the loss of time and labor incident to first cutting off the nuts from the fastening bolts, used in connection with present standard equipment.

With the foregoing and other objects in view that will readily appear as the nature of my invention is better understood, the same consists in the novel features of construction, combination and arrangement of parts illustrated in the accompanying drawings and more particularly pointed out in the appended claims.

In the accompanying drawings, which are for illustrative purposes only and are therefore not drawn to scale:

Figure 1 is a side elevation, illustrating the application of my invention.

Figure 2 is an enlarged detail plan view of one of the brake beam safety guides, a portion of the sand-bar shown in dotted lines.

Figure 3 is a central longitudinal section, taken on line 3—3 of Figure 2, looking in the direction indicated by the arrows.

Figure 4 is a vertical transverse section, taken on line 4—4 of Figure 3, looking in the direction indicated by the arrows.

Figure 5 is a similar view, taken on line 5—5 of Figure 3, looking in the direction indicated by the arrows.

Figure 6 is also a vertical transverse section, taken on line 6—6 of Figure 3, looking in the direction indicated by the arrows and Figure 7 is a horizontal section, taken on line 7—7 of Figure 3.

Referring to the drawings for a more particular description of my invention and in which drawings like parts are designated by like reference characters throughout the several views, A designates the truck of a railway car or coach, B the brake shoes, C the brake beams and D the sand-bar. These

parts are of the usual form or construction used in present standard equipment and hence, no further explanation in this connection is thought necessary.

In carrying out my invention, each brake beam safety guide 1 is preferably formed from a single elongated strip or piece of steel having a flat upper surface 2 which is slightly curved or inclined upwardly, as shown more particularly in Figure 3. Each safety guide is formed at the inner end with an inwardly extending tongue 2 which extends under and fits against the bottom of the sand-board D, leaving a shoulder 3 at the junction of the tongue with the body portion of the safety guide which fits against the adjacent side edge of the sand-board.

As shown, each safety guide is detachably secured to the sand-board by the vertical substantially inverted L-shaped hanger or clip 4. The longer leg or member 5 of each hanger or clip is provided at its lower end with a reduced cylindrical shank or stem 6 which extends through a corresponding longitudinally disposed elongated slot or opening 7 formed in the tongue of the corresponding safety guide and terminates in an elongated head 8 which normally extends across or transversely of its slot 7.

The hangers or clips fit over or engage the corresponding flanges 9 of the sand-board and an elongated clamping block 10 is employed in association with each hanger or clip. These clamping blocks extend transversely of the safety guide and are formed with inclined inner edges 11, which fit against the inner walls of the sand-board flanges. The clamping blocks are secured to the upwardly extending shanks or stems 12 of the pins 13 by the cotter pins 14. The body portions 15 of the pins 13 extend through corresponding vertical openings 16 in the tongues of the safety guides and are formed with heads 17 which bear against the bottoms of the aforesaid tongues.

By means of my connections, the safety guides may be quickly and easily applied or removed, and there is no possibility of the guides working loose or falling from place.

From the foregoing description taken in connection with the drawings, it is thought that the construction, operation and advantages of my invention will be readily understood without requiring a more extended explanation.

Having described my invention, what I claim as new and desire to secure by Letters Patent, is:

1. In a device of the character specified, a
5 brake beam safety guide, and means for de-
tachably securing the safety guide to the
sand-bar, said means comprising a vertical
hanger carried by the guide and fitting over
10 the corresponding side flange of the sand-
bar and a clamping block carried by the
guide and engaging one side wall or face of
said flange.

2. In a device of the character specified, a
15 brake beam safety guide and means for de-
tachably securing the safety guide to the
sand-bar, said means comprising a vertical
hanger having a removable slot and head
connection with the guide and fitting over
20 the corresponding flange of the sand-bar and

a removable clamping block carried by the 20
guide and fitting against the inner side wall
of said flange.

3. In a device of the character specified, a
25 brake beam safety guide and means for de-
tachably securing the safety guide to the
sand-bar, said means comprising a vertical
substantially inverted L-shaped hanger hav-
ing a removable slot and head connection
20 with the guide and fitting over the corre-
sponding side flange of the sand-bar, a 30
clamping block bearing against the inner
side wall of said flange and a headed pin and
cotter for detachably securing the clamping
block to the guide.

In testimony whereof he affixes his signa- 35
ture.

FIRMIN M. LE COMTE.
